GARMENT HANGER

Jacob J. Podell, New York, N. Y.

Application September 25, 1951, Serial No. 248,186

12 Claims. (Cl. 223—91)

1 The present invention relates to hangers for garments and other articles and more particularly to a garment hanger of the type adapted to be used for holding a pair of trousers suspended by the cuffs, in inverted position.

Various types of garment hangers and trouser hangers have been devised. Many have been unduly complicated and too impracticable to go into commercial manufacture and sale, and others have been of such faulty design that they fail to securely grip and hold a garment or other article against slipping out and dropping onto the floor, particularly after the hanger has been in use for a time. Still others have been objectionable in that they required an undue amount of study and instruction before a person was able to operate them.

The present invention aims to overcome the above and other difficulties or disadvantages by providing a new and improved garment hanger of relatively simple construction and operation, which securely grips a garment against unintentional release, and yet which quickly releases its grip upon actuation of a relatively simple release mechanism.

An object of the present invention is to provide a new and improved garment hanger.

Another object of the invention is to provide an improved garment hanger which is particularly adapted to grip and hold the cuff portions of a pair of trousers.

Another object of the invention is to provide a trouser hanger of relatively simple construction and operation.

Another object of the invention is to provide an improved trouser and coat hanger.

Still another object of the present invention is to provide a trouser hanger embodying operation means that may be readily operated to close and open its trouser gripping portions.

Other and further objects of the invention will be obvious upon an understanding of the illustrative embodiment about to be described, or will be indicated in the appended claims, and various advantages not referred to herein will occur to one skilled in the art upon employment of the invention in practice.

A preferred embodiment of the invention has been chosen for purposes of illustration and description and is shown in the accompanying drawings, forming a part of the specification, wherein:

Fig. 1 is a side elevational view showing one form of the present invention;

Fig. 2 is a top plan view of the trouser supporting portion of the hanger shown in Fig. 1;

Fig. 3 is a sectional view taken along line 3—3 of Fig. 2;

Fig. 4 is an enlarged sectional view taken along line 4—4 of Fig. 1;

2 Fig. 5 is an end view of the trouser supporting device shown in Fig. 1, with a pair of trousers gripped thereby;

Fig. 6 is a cross sectional view showing the trouser supporting device of the present invention with its clamping jaws fully open;

Fig. 7 is a fragmentary bottom plan view showing the trouser hanger with its jaws open; and

Fig. 8 is an end view, partly in section, showing the trouser hanger of the present invention with a supporting hook directly connected thereto.

Referring more particularly to Fig. 1 of the drawings, there is shown a hanger comprising a coat-hanging portion 2 having a supporting hook 4 and carrying at its underside a trouser hanger 5. The trouser hanger is secured adjacent its opposite end portions to the underside of the coat supporting portion 2 and is illustrated in greater detail in Figs. 2 through 6.

As shown in Figs. 2—6, the trouser hanger portion comprises what for convenience will be termed a "base member" 7 of any suitable length, to opposite end portions of which are secured upwardly extending brackets 8 of suitable shape or design. The brackets may be riveted or otherwise secured to the base member 7 and extend upwardly for permanent or temporary connection with the coat-supporting portion 2 or any other movable or fixed structure. The means shown gripping the cuff or bottom ends of a pair of trousers comprises a downwardly extending bar member or plate member 10, at opposite sides of which are located clamping jaw members 11 and 12, all of any suitable length. The bar member 10 is movable up and down, by an operating mechanism to be hereinafter described, and is operatively connected with the jaw members 11 and 12 so that the latter members move toward the bar member during its upward movement and move away from the bar member during its downward movement. Hence during upward movement of the bar member 10 both jaws 11 and 12 come together to grip one trouser cuff placed between the bar member and jaw member 11, and the other trouser cuff placed between the bar member and the opposite jaw member 12. Release of the trouser cuffs occurs when the bar member 10 moves downwardly and the clamping jaws 11 and 12 spread apart with respect to the bar member.

The clamping jaws 11 and 12 are operatively interconnected by cross-bars 14 and 15, secured to opposite ends of the center bar member 10. The upper ends of the clamping jaws 11 and 12 are provided with integrally formed operating arms 19. One operating arm 19 is preferably provided at each end of each jaw member 11 and 12, and the upper end of the arm may have an aperture 20 therein which extends about a pin 21 that projects inwardly from the crossbar; if de-

sired the aperture may be provided in the cross-bars 14, 15 and the pins on the arm 19. Each of the clamping jaws 11 and 12 is thus rotatably supported at its opposite ends by the spaced crossbars 14 and 15. The arms 19 preferably extend through openings or slots 9a in laterally projecting flanges 9 of the base member 7. Each of the arms 19 has adjacent its upper portion a projecting lug 23 for contacting a portion of a flange 9. Each lug 23 insures pivoting of a respective arm 19 and a respective connecting jaw about the supporting pins 21 as the central bar member 10 approaches a lowermost position, as will be hereinafter described.

As the central bar 10 moves downwardly from the position illustrated in Figs. 4 and 5, the cross-bars 14 and 15 are also moved downwardly and the latter carry with them the depending arms 19 and jaw members 11 and 12. During this downward movement lower portions of the jaw-supporting arms 19 move out of the slots 9a in the base member 7 and the jaws are free to gradually move away from the central bar member 10.

When the laterally projecting lugs 23 at the upper ends of the arms 19 strike adjacent stationary portions 25 of the base member 7, the arms are forced positively to rotate outwardly about their retaining pins 21 and the jaws are spread in positive manner outwardly away from the central bar member 10. In this relationship articles, for example, the cuffs of a pair of trousers, may be freely placed between the jaw members and opposite faces of the central bar member 10. Preferably each of the jaw members 11 and 12 has an enlarged gripping face, 11' and 12', respectively, for clamping against a trouser cuff to hold it in position. These gripping faces and the faces at opposite sides of the central member 10 may be slightly roughened to give an improved grip on the trousers.

After insertion of the ends of the trouser legs between the central bar and the respective outer clamping jaws 11 and 12, the central bar 10 may be moved upwardly. As the bar 10 moves upwardly it carries with it the crossbars 14 and 15 and the clamping jaws 11 and 12 which are rotatably connected therewith. As the crossbars 14 and 15 lift the connecting arms 19, outer faces 26 of the latter move along inwardly facing edges 28 of the openings 22 in the base member 7; as the arms 19 continue their upward movement a "camming" action takes place which directs the arms 19 and their connected jaws 11 and 12 inwardly toward the central member. The inward movement may be facilitated by having the outer edge 26 inclined as shown so that as it moves upwardly there is an increased tendency to force the arms and jaws inwardly. When the central member and jaws, together with their interconnecting portions, reach an upper position such as illustrated in Fig. 5, the portions 24 of a pair of trousers are firmly held between adjacent gripping faces of the hanger.

Up and down movement of the central member to close or open the clamping jaws 11 and 12 may be provided by a screw type operating means. As shown, for example in Figs. 3 and 4, the "stationary" base member 7 has secured thereto an upwardly extending hollow member or sleeve 31 which contains the operating screw means. An exteriorly threaded member 32 is secured by a pin 34 to an appropriate portion of the central member 10 and a hollow interiorly threaded member 35 engages with the exteriorly threaded member 32. The interiorly threaded member 35

is provided with an annular recess 37 into which projects a portion of the stationary outer hollow sleeve 31. This interfitting recess and projection hold the outer sleeve 31 and interiorly threaded hollow member 35 against endwise movement with respect to each other and permit rotation of the interiorly threaded member. To facilitate such rotation the upper end of the threaded member 35 may be provided with an enlarged operating head or knob 40.

As the operating head 40 is turned in one direction its threaded interconnection with the exteriorly threaded screw 32 causes the latter to move downwardly. Since this member 32 is secured to the central bar member 10 the latter member also moves downwardly and the clamping jaws open, as previously brought out. When the operating head 40 is rotated in an opposite direction the inner threaded member 32 is caused to move upwardly within the interiorly threaded member 35, to thus raise the central bar member 10 and bring the clamping jaws inwardly toward it, so as to grip a portion of a garment.

When the jaws 11 and 12 are in clamping position against a portion of a garment, as illustrated for example in Fig. 5, the operating knob or head 40 may be released and the jaws remain in the adjusted clamping position. There is no tendency for the weight of the garment to open the jaws and let the garment fall on the floor. The operating knob 4 may be readily turned and the very nature of the device makes it obvious to a person how it should be used; the natural tendency is for a person to turn the knob which is disposed clear of any clamping parts and is in such position that it may be easily rotated. To further bring out the manner of operation, the knob 40 may be provided with knurling; when a person sees that the knob is knurled it is even more obvious to him that the knurl is applied so that one may grasp and rotate the knob with his fingers.

As previously referred to, the trouser supporting portion of the present hanger may be secured to the underside of the coat supporting portion 2 by brackets 8. In this relationship the operating knob 40 is so disposed that it may be readily turned to grip or release a pair of trousers. After a pair of trousers is inserted and gripped between the jaws and central member a coat may be placed over the upper portion 2, and the entire hanger supported in the usual manner by the hook 4.

In Fig. 3 the present invention is shown without the coat-supporting portion 2. The trouser hanger device shown in this latter figure has a supporting hook 44 secured to the threaded member 32a to thereby facilitate hanging the device on a closet crossbar or the like. In this form of the invention the supporting brackets 8 shown in Fig. 1 may be omitted. Most men own a greater number of pairs of trousers than they do complete suits and hence they may desire to have a number of trouser hangers without the upper coat supporting part shown in Fig. 2. The device in Fig. 3 is designed to supply this requirement.

It is believed that the operation of the present garment hanger will be clear from the foregoing description and the drawings and hence it is not being repeated at this time.

It will be seen that the present invention provides a new and improved hanger of relatively simple construction and operation which is adapted to hold a garment, a pair of trousers, towels, or other articles of any sort firmly in

position and which is adapted to be operated by persons of average intelligence without the need of special instructions. The hanger may be constructed entirely of metal parts suitably riveted, welded, or otherwise joined together or it may be made of wood, plastic, metal, or combinations thereof. For example, the central member 19, clamping jaws 11 and 12, and base member 7 may be made of wood in order to conserve metal.

As various changes may be made in the form, construction and arrangement of the parts herein without departing from the spirit and scope of the invention and without sacrificing any of its advantages, it is to be understood that all matter herein is to be interpreted as illustrative and not in a limiting sense.

I claim:

1. An article hanger comprising a bar member, a separate jaw member at each side of said bar member, means operatively interconnecting said members for closing movement of the jaw members with respect to the bar member to grip an article therebetween, means for freely engaging said jaw members mounted for reciprocation with respect to said bar member, means operatively connected with said bar member and said jaw engaging means for reciprocating said jaw engaging means with respect to said bar member.

2. A garment and article hanger comprising a downwardly extending bar member, a jaw member at one side of said bar member, means including a crossbar secured to and extending laterally from said bar member operatively connected with said jaw member for moving the jaw member toward the bar member to grip a portion of a garment or article between said members, additional jaw moving means mounted for reciprocation with respect to said bar member, means operatively connected with said bar member and said additional jaw moving means for reciprocating said additional jaw moving means with respect to said bar member.

3. A hanger having a base member, support means projecting from said base member, a bar member extending longitudinally of said base member, said bar member mounted for relative movement with respect to said base member, means for relatively moving said members toward and away from each other, a retaining jaw extending generally longitudinally of said members, means swingably connecting said retaining jaw with a first one of said members and means on the other member engageable with portions of said jaw for movement toward and away from said first member during relative movement of said bar and base members.

4. In a garment hanger having upwardly extending means for suspending the hanger from a support, a base member carried thereby, a bar member extending along said base member, means operatively connecting said members for relative movement generally toward and away from each other, a clamping jaw pivoted to one of said members for swinging movement toward and away from said member, and means carried by the other member adapted to operably engage said jaw during said relative movement of the members to swing the jaw to close and open a garment-gripping mouth between said jaw and the member to which it is pivoted.

5. In a garment hanger having means for suspending the hanger from a support, a base member carried thereby, a bar member extending along said base member, means operatively connecting said members for relative movement gen-

erally toward and away from each other, a clamping jaw movably mounted on said bar member for swinging movement toward and away from said bar member, and means carried by said base member adapted to operably engage said jaw during said relative movement of the members to swing the jaw to close and open a garment-gripping mouth between said jaw and said bar member.

6. In a hanger for garments and the like having means for suspending the hanger from a support, a base member carried by said means, a bar member extending along said base member, a clamping jaw generally parallel to said bar member, and an arm rigidly extending from said jaw and pivotally connected said bar member for swinging movement toward and away from the bar member, a portion of said base member being adapted to operably engage said arm during said swinging movement to close and open a gripping mouth between said jaw and said bar member.

7. A hanger as claimed in claim 6, in which said portion of the base member comprises a surface thereof adjacent an edge of said arm and engageable therewith during said swinging movement for directing said arm and jaw toward the bar member.

8. A hanger as claimed in claim 6, in which said arm has an inclined surface at one edge thereof and said portion of the base member comprises a surface thereof adjacent said inclined surface and engageable therewith during said swinging movement for directing said arm and jaw toward the bar member.

9. A garment hanger comprising a base structure, a bar member connected to the base structure for vertical reciprocation with respect to the base structure, means for reciprocating said bar member with respect to the base structure, a clamping jaw extending generally parallel to said bar member and pivotally connected thereto and having an inclined camming surface and a surface formed on said base structure and contacting a portion of said inclined camming surface for directing the jaw to swing about said pivotal connection toward the bar member to clamp a portion of a garment against the bar member upon reciprocation of said bar member.

10. A garment hanger as claimed in claim 9, in which a clamping jaw is provided at each side of the bar member and in which a surface is provided on said base member for directing each clamping jaw toward the bar member.

11. A garment hanger as claimed in claim 9, in which the pivotal connection of the jaw to the bar member includes an arm on said jaw, and in which said arm contacts a portion of the base structure to insure opening movement of the jaw with respect to the bar member upon reciprocation of the latter.

12. A hanger as claimed in claim 9, in which the means for reciprocating the bar member with respect to the base structure comprises a first threaded member secured to and extending upwardly from the bar member and a rotatable threaded member in engagement with the first threaded member and operatively connected with said base structure.
